(57) **CLAIM**

The ornamental design for a curved drywall bead with
perforated flaps, as shown and described.

DESCRIPTION

FIG. 1 is a perspective view of a drywall bead with perforated flaps showing my new design, the right end portion
shown broken away to indicate indeterminate length;
FIG. 2 is a left end view thereof, the right end being a mirror
image;
FIG. 3 is a detailed view, in enlarged scale, taken from the
oval identified by the numeral 3 in FIG. 1;
FIG. 4 is a broken top view thereof; and,
FIG. 5 is a broken bottom view thereof.
